By Rufus Bennett Fowler, Atty.

UNITED STATES PATENT OFFICE.

JOSEPH WALTER FLAGG, OF WORCESTER, MASSACHUSETTS.

AUTOMATIC CASH-CARRIER.

SPECIFICATION forming part of Letters Patent No. 316,531, dated April 28, 1885.

Application filed October 18, 1884. (No model.)

To all whom it may concern:

Be it known that I, JOSEPH WALTER FLAGG, a citizen of the United States, residing at Worcester, in the county of Worcester and State 5 of Massachusetts, have invented certain new and useful Improvements in Automatic Cash-Carriers, of which the following is a specification, accompanied by illustrative drawings, in which—

10 Figure 1 shows a side elevation of the inclined tracks upon which the rolling carriers are conveyed to and from the sales-counters and the cashier's desk. Fig. 2 is a detached view of the elevator in its lowest position. 15 Fig. 3 is a top view of the same. Fig. 4 is a side elevation of a portion of the outward way, showing the attached intermediate way and connected devices for checking the passage of the carrier. Fig. 5 is a top view of 20 the intermediate way removed from the outward way on line x x , Fig. 1. Fig. 6 is a perspective view of the tilting gate. Fig. 7 represents, partly in section, the device for suspending the rails forming the tracks. Fig. 25 8 shows one of the rolling carriers. Fig. 9 shows one of the hemispheres forming the rolling carrier, with its inclosing-bands removed, and Fig. 10 shows one of the inclosing-bands removed from the carrier.

30 Similar letters refer to similar parts in the several views.

My present invention relates to a cash-carrying apparatus in which an inward-inclined track, A, is used to convey rolling cash-carriers to the cashier's desk, and an outward-inclined track, B, is employed to return them from the cashier's desk to the several salesmen; and it consists in an improved elevator for raising the cash-carriers from the salesmen 35 to the inward track; in an improved method of suspension of the tracks, whereby the noise of the rolling carriers as they pass over the rails is to a great extent obviated; in intermediate ways or tracks placed below the outward way, having devices for retaining the carriers therein when the delivery-baskets are drawn down, and the construction of the rolling cash-carriers.

The elevator C consists of a cage or box, C', 50 adapted to hold the carrier while it is being raised, and of discharging it upon the inward track at the proper time, mounted upon a

series of pivoted bars arranged in pairs, the upper bars, a a , being pivoted at their upper ends to the lower side of the cage C', and at 55 their lower ends to the upper ends of the bars b b , which are pivoted together at their centers, and have their lower ends pivoted to the upper ends of the bars c c , likewise pivoted at their centers and at their ends to the bars 60 d d ; these in the same manner to e e ; these to f f , and these to g g , which are pivoted at their centers by a rod, h , held by the guide-rods h' h' , between which the elevator moves. It will be seen that one half of each pair of bars, with 65 the adjacent half of the contiguous pair, forms in Fig. 1 a lozenge-shaped figure, E, with its vertical diameter the longest. If the lower ends of the bars g g be pushed upward and outward by means of the short bars g' g' , the 70 upper ends of g g will be carried downward and outward, producing a simultaneous movement throughout the series of pivoted bars, causing them to assume the position shown in Fig. 2, in which the horizontal diameters of 75 the lozenge-shaped figure E become the longest and the elevator lowered.

The carrier D may be placed in a cage or box, C', which is open on the side next the track, the carrier D being held in place by the 80 rod h^2 until the track A is reached, when the carrier rolls out upon the track, or a tilting device—such as was shown in the Letters Patent of the United States No. 274,302, granted to me, and dated March 20, 1883; or other 85 means may be employed for ejecting the carrier from the elevator onto the inward track, my present invention relating only to the device for raising and lowering the carrier.

The rails forming the tracks I suspend by 90 the rods i i from a yoke, H, which is suspended from the rod j . It has been customary to place a strip of leather, rubber, or some similar substance upon the surfaces of the rails coming in contact with the rolling carriers to decrease 95 the noise. I accomplish the same result by placing between the tracks and the suspending-rods a body with a small sound-conducting power, thereby insulating the tracks by a non-conductor of sound. This feature of my 100 invention is conveniently embodied in the form shown in Fig. 7, and consists in placing a sleeve, k, of leather, felt, or some analogous material, about the rod j where it passes

through the yoke H, a flange, k', separating the yoke from the nut l on the rod j, thereby cutting off all sound-vibrations communicated through the yoke H from the rod j and materially lessening the noise produced by the rolling carriers.

Instead of a nut, l, a bead may be formed on the rod j to support the yoke H.

The outward way, B, has at F a circular opening, similar to the circular openings in the outward track (shown in the Letters Patent No. 274,302) above referred to, permitting the cash-carriers to fall through upon one end of the intermediate track, G, suspended beneath the track B.

A receiving-basket, I, is held against the under side and at the lower end of the intermediate track, G, by cords m, attached to winding-drums J on the track B.

Between the rails of the track G, and above the basket I, is a tilting gate, K, consisting of a rectangular frame, K', large enough to allow the carriers to pass through, and journaled by bearings n n in the rails, and having an arm, o, on its outer and lower side resting upon the basket I, and serving also as a weight, so that when the basket is drawn down, as shown in Fig. 4, the weighted side of the tilting gate will fall, raising the opposite side above the way G, so as to check the passage of the carriers. As the basket is again drawn up by the winding-drums the gate K will be returned to and held in the same plane as the way G, allowing the carriers to pass through into the receiving-basket I, as shown in Fig. 1.

1. A pin projecting from the inner side of one of the rails, but not shown in the drawings, retains the tilting gate in the position shown in Fig. 4.

4. The carriers consist of hollow spheres formed of the hemispheres L L', adapted to contain the cash and to roll upon the inclined ways, the two hemispheres being provided with some one of the several well-known means for locking them together. The hemispheres I make of wood, papier-maché, rubber, or leather-board, or similar material, and I form a recess, p, around each hemisphere adjacent the plane surfaces, to receive a metallic band, p', and a similar recess, q, at right angles with the plane surfaces, to receive the band q'. These recesses are of the same depth as the metallic bands p' and q', so they will not project upon the outside of the carrier.

5. By this method of construction I prevent the carriers from splitting, in case they are thrown from the elevators or tracks upon the floor.

The bands p' may be used alone, or the band q separately; but I prefer to unite them, forming a basket, as shown in Fig. 10. If the bands p' and q' are used together and joined at r r, no mode of fastening to the carriers is necessary; but in case either of the bands p' or q' are used separately, pins or screws passing through the bands into carriers may be employed to secure the bands.

I am aware that a series of parallel and

pivoted bars or "lazy-tongs" have been used to effect the carriage of parcels or cash-receptacles from one station to another, moving along the line of a track or guide-wire. Such I do not claim; but

What I claim as my invention, and desire to secure by Letters Patent, is—

1. The combination, with the inward-inclined way of a cash-carrying system, of a series of parallel and pivoted bars or lazy-tongs moving in vertical guiding-rods, vertical guiding-rods k', cage or box for retaining the carrier in its passage and allowing it to pass onto the inward-inclined way, and actuating mechanism for operating the said lazy-tongs, as and for the purpose set forth. 75

2. The combination, with the ways of a cash-carrying system and rods supporting said ways, of non-sound-conducting sleeves or ferrules interposed between said rods and the contact of said ways, whereby the ways are insulated and the communication of the sound-vibrations from the rolling carriers cut off 90 from said supporting-rods, as and for the purpose set forth.

3. The combination, with the ways of a cash-carrying system and supporting-rods j and yokes H, of the sleeves k, inclosing the rods and cutting off the contact of the yokes H, as set forth and described. 95

4. The combination, with the outward way of a cash-carrying system having openings to allow the carriers to pass, and vertically-moving receiving-baskets, of a short way suspended beneath the openings of the main outward way and between said way and the receiving-baskets, and a tilting gate in said suspended way, substantially as described, and 100 operated by the receiving-basket, so the passage of the carriers from said suspended way will be determined by the position of the receiving-basket, as and for the purpose set forth. 105

5. The combination, with the outward way, B, of receiving-track G, tilting gate consisting of a frame, K', journaled in the way G, and having an arm, o, as and for the purpose set forth. 110

6. The cash-carrier consisting of a hollow sphere formed of two hemispheres properly locked together, and having one or more metallic bands extending around each hemisphere, said bands being recessed, so as to bring the bands flush with the outer surface of the hemispheres, as and for the purpose set forth. 115

7. The cash-carrier consisting of the hemispheres L L', having inclosing-bands p' and q', joined together and recessed in the hemispheres, as and for the purpose set forth. 125

Signed at Worcester, in the county of Worcester and State of Massachusetts, this 16th day of October, 1884.

JOSEPH WALTER FLAGG.
